ATTACHMENT FOR CONTAINER CARRIERS

Frederick K. Fildes, Altoona, Pa.

Application August 10, 1933, Serial No. 684,482

5 Claims. (Cl. 105—366)

This invention relates to container carriers, such as railway cars, motor trucks, or trailers, and more specifically to attachments for holding a container against shifting while it rests on the carrier, yet facilitating its removal incident to the raising of the container a relatively short distance above its seat. In certain respects the invention represents an improvement upon the type of container carrier disclosed in U. S. Letters Patent No. 1,845,594, granted to me on February 16, 1932.

One object of the invention is to provide, in combination with a carrier having container seating attachments, a series of abutments which are adapted to restrain lateral shifting of a container and which are movable automatically to positions above and beneath the container seats incident to the operations of lowering and raising the container with respect to the carrier. Another object of the invention is to provide container seating attachments and shift-restraining abutments disposed along the sides of the car, with the movable abutments located beyond the side sills of the car, and with their operating means so incorporated in the car as to leave a substantially unobstructed floor space, whereby the car may be readily converted to other uses than for the carriage of containers.

Other objects and advantages characteristic of my present invention will become more fully apparent from the description hereinafter set forth of one embodiment or example of the practice of the invention, having reference to the accompanying drawings, whereof:

Fig. I represents a part side elevation of a railway flat car fitted with attachments of my invention.

Fig. II represents a cross section of the same, taken as indicated by the lines II—II of Fig. I.

Fig. III represents an enlarged plan view of one container seating attachment and associated parts, with the car floor removed and certain parts broken away for clearness of illustration, and showing portions of two adjacent containers in dot-and-dash lines.

Fig. IV represents a cross section of the same, taken as indicated by the lines IV—IV of Fig. III.

Fig. V represents a cross section of the same, taken as indicated by the lines V—V of Fig. III.

Fig. VI represents a perspective view of the lower portion of the shaft bearings illustrated in Fig. V.

Fig. VII represents a perspective view of one of the container seating attachments and adjacent portions of the car floor and side sill.

Fig. VIII represents a perspective view of a crank arm associated with one of the movable shift-restraining abutments; and,

Fig. IX represents a perspective view of one of the movable shift restraining abutments.

With particular reference to Fig. I of the drawings, the numeral 1 designates comprehensively a portion of a railroad flat car, and 2 the floor or platform thereof. The car is substantially unobstructed throughout its central floor space.

At spaced intervals along the side sills 3, there are fixed attachments designated at 4, 4'. In view of the fact that the several attachments are duplicates of one another, excepting the end ones 4', the following description is limited to an explanation of one individual attachment, thereby avoiding repetition.

Each fixed attachment 4, in the illustrated example of my invention, is in the form of a casting having an upstanding central abutment 5 which extends transversely of the car floor 2 for a short distance from the sides of the car, and which serves to prevent longitudinal shifting of containers, such as illustrated at A, on the car.

The central abutment 5 has at the top thereof inclined surfaces 6 which assist in guiding the containers A to their proper seated positions. At each side of the central upstanding abutment 5 there are horizontal surfaces 7 which serve as seating surfaces for the bottom corners of two adjacent containers A. The base of each attachment 4 is formed with a vertical depending flange 8 which is riveted to the web of the side sill 3, and with a horizontal flange 9 which is attached to the top surface of the side sill 3. The detailed construction of the attachment 4 is most clearly illustrated in Fig. VII. Each attachment 4 has pivoted thereon a pair of swinging abutments 10, one for the container seated at one end of the attachment, and the other for the container seated at the other end of the attachment. Each attachment 4 also includes ledges 11 formed at the ends thereof which serve as stops limiting the swinging movement of the movable abutments 10.

The end attachments 4' in most respects structurally conform with the foregoing description of the intermediate attachments 4 except that they are shaped to accommodate only one swinging abutment 10, and further explanation thereof is deemed unnecessary.

The movable shift restraining abutments 10, which are illustrated most clearly in Fig. IX, are each in the general form of a flat plate reinforced by a rib 14. Each abutment is preferably formed at its inside top corner with an inclined

surface, as indicated at 15, which serves to guide the corner of a container when the container is lowered onto its seat. Each movable abutment 10 is mounted on an actuating shaft 16 which extends inwardly along the floor 2 of the car from the attachment 4, 4', the shaft being mounted at its outer end in a bearing 17, which forms a part of the attachment 4, 4', and being mounted at its rear end in a bearing 18 which is secured to the underframe of the car, in the illustrated example, by means of a longitudinally extending Z-bar 19.

The rear bearing 18 is most clearly illustrated in Figs. V and VI, and is desirably formed of two pieces, one piece 30 comprising a flat plate with part cylindrical formations 31 at the ends thereof, as shown in Fig. VI, and the other piece 32 fitting on top thereof, and having part cylindrical formations 33 which form with the corresponding formations of the piece 30 cylindrical openings for the reception of the shaft 16. Both pieces 30, 32 are joined together and secured to the underlying Z-bars 19.

The actuating shafts 16 for the movable abutments 10 are of circular cross section at the regions within the front bearing 17 and the rear bearing 18, and are of square or nut-shaped cross section at the intermediate regions 20. The actuating shafts 16 are desirably formed at their rear ends with shoulders 21 which engage the rear bearings 18 and prevent their removal. On each actuating shaft 16, at the nut-shaped portion 20 thereof, there is mounted a crank arm 22 which is in the form of a shoe having a smoothly rounded surface 23 adapted to engage the bottom of a container as it is lowered onto the railway car. The crank arms 22 are most clearly shown in Figs. IV and VIII, and are desirably reinforced by stiffening ribs 24 which extend substantially at right angles to the rounded surfaces 23.

It will be observed that each intermediate attachment 4 is provided with corner seats 7 for two adjacent containers and with a pair of actuating shafts 16 and crank arms 22, one crank arm being adapted for engagement with one container, and the other crank arm being adapted for engagement with the next adjacent container. To permit the installation of the actuating shafts 16, the crank arms 22, and the bearings 18, the car floor 2 is cut away in the vicinity of these parts. Moreover, at the sides of the car elevated supports for the containers, in the form of narrow wood strips 26, are preferably employed. The supporting strips 26, which are most clearly illustrated in Fig. VII, extend longitudinally from one attachment 4 to another, and cause the containers to be raised slightly above the car floor 2, thus affording ample space for the disposition of the actuating shafts 16 and the rear bearings 18 between the car floor and the bottom surfaces of the containers.

The operation of the above described container carrier is as follows: In the event that containers A are to be transferred onto the railway car 1 by overhead hoisting apparatus, the operator proceeds to lower a container onto the car in a position directly above and square with the seating space into which the container is to be lowered. Incident to the lowering of the container, its bottom surface will strike the curved surfaces 23 of the crank arms 22 and cause the actuating shaft 16 to be rotated. With rotation of the actuating shafts 16 the movable abutments

from positions beneath the top surfaces of the elevated strips 26 and corner seats 7 to positions above the same, as represented at the left hand of Fig. I. Moreover, while the container is being thus lowered onto the floor of the car, it will be guided in its movement by engagement with the inclined surfaces 6 of the upstanding rigid abutments 5. After one or more containers have been thus deposited upon the car, the movable abutments 10 will be effective to prevent lateral shifting of the containers, and the upstanding rigid abutments 5 will be effective to prevent longitudinal shifting of the containers.

When a container is removed from the car by means of an overhead hoist, as soon as the bottom surface of the container is raised a short distance above the car floor 2, the corresponding set of movable abutments 10 will fall by gravity, to positions beneath or substantially level with the top surface of the supporting strips 26 and the corner seats 7, with upward swinging of the crank arms 22. The parts will then assume the positions illustrated at the right hand of Fig. I. Accordingly, when a container has thus been raised a slight distance above the car floor, it is in readiness to be shifted laterally to a truck or station platform or any other location where it is desired to place the container.

It is to be particularly noted that the container carrier of this invention can be used with many types of container transfer apparatus, and that inasmuch as the central floor space of the carrier is unobstructed, the carrier may at once be converted to ordinary flat car use. Moreover, the container carrier of this invention is particularly useful where containers are shifted by hand-operated hoisting apparatus, for the containers need only be raised a short distance above the carrier floor preparatory to their lateral shifting onto or off the carrier.

While I have described and illustrated one particular example of my invention, it will be apparent that various changes may be made in the form of the apparatus disclosed without departing from the spirit of the invention as defined in the annexed claims.

Having thus described my invention, I claim:

1. In combination with a container carrier, spaced container supporting attachments on the sides of the carrier, container shift-restraining abutments pivotally mounted on said attachments beyond the sides of the carrier and normally urged by gravity to depressed positions not obstructing the lateral transfer of containers, shafts connected to and extending from said abutments inwardly along the floor of the carrier, and crank arms on said shafts adapted to engage the bottom of a container, said crank arms serving to raise the abutments to operative shift-restraining positions incident to the lowering of a container onto the carrier.

2. In combination with a container carrier, spaced container supporting attachments on the sides of the carrier, said attachments including abutments extending transversely of the car floor and effective to prevent longitudinal shifting of a container, additional abutments for preventing lateral shifting of the container pivotally mounted on said attachments beyond the sides of the carrier and normally urged by gravity to depressed positions below the container supporting surfaces of said attachments, shafts connected to and extending from said abutments inwardly along the floor of the carrier, and crank arms on said shafts adapted to engage the bottom of a

container, said crank arms serving to raise the lateral shift-restraining abutments incident to the lowering of a container onto the carrier.

3. In combination with a container carrier, spaced container supporting attachments on the sides of the carrier having seats above the top surface of the floor of the carrier, container shift-restraining abutments pivotally mounted on said attachments beyond the sides of the carrier and normally assuming positions beneath said container seats, shafts connected to and extending from said abutments inwardly along the floor and beneath the container seats, and crank arms on said shafts adapted to engage the bottom of a container, said crank arms serving to raise the abutments to operative shift-restraining positions incident to the lowering of a container onto the carrier.
4. In combination with a container carrier, spaced attachments on the sides of the carrier having seats adapted to support the corners of two adjacent containers, container shift-restraining abutments pivotally mounted on said attachments beyond the sides of the carrier and nor-

mally assuming positions beneath said corner seats, shafts connected to and extending inwardly from said abutments along the floor of the carrier, and crank arms on said shafts adapted to engage the bottom of a container and serving to raise the abutments to operative shift-restraining positions incident to the lowering of a container onto the carrier.

5. In combination with a container carrier, spaced attachments on the sides of the carrier having seats adapted to support the corners of two adjacent containers, a pair of container shift-restraining abutments pivotally mounted on each said attachment beyond the sides of the carrier and normally assuming horizontal positions beneath said corner seats, shafts connected to and extending inwardly from each said abutment along the floor of the carrier, and crank arms having smoothly rounded ends adapted to engage the bottoms of the containers and serving to raise the abutments to operative shift-restraining positions incident to the lowering of the containers onto the carrier.

FREDERICK K. FILDES.
